UNITED STATES PATENT OFFICE.

ALEXANDER C. MCCLURE, OF PADUCAH, KENTUCKY.

WHEEL-FLANGE-LUBRICATING DEVICE.

1,317,449.

Specification of Letters Patent. Patented Sept. 30, 1919.

Application filed August 29, 1917. Serial No. 188,782.

To all whom it may concern:

Be it known that I, ALEXANDER C. MCCLURE, a citizen of the United States, residing at Paducah, in the county of McCracken and State of Kentucky, have invented certain new and useful Improvements in Wheel-Flange-Lubricating Devices; and I do hereby declare the following to be a full, clear, and exact description of the invention, such as will enable others skilled in the art to which it appertains to make and use the same.

This invention relates to improvements in lubricating devices for flanges of locomotive wheels, and the primary object of the invention is to provide a lubricator of this type, which includes a lubricant conveying tube mounted in such a novel manner that the same will accompany the flange of the wheel during any movement of the wheel in a vertical or lateral direction.

Another object of the invention is the provision of a lubricator of this type having a reservoir including strainers located, respectively, at the inlet and discharge ports of the reservoir, so as to insure of the oil in passing from the reservoir being free of all foreign matter.

A further object of the invention is the provision of a lubricator of this nature that will be efficient and durable and one in which the component parts thereon are arranged in a convenient and compact manner.

Other objects will appear and be better understood from that embodiment of my invention of which the following is a specification, reference being had to the accompany drawings forming a part thereof, in which:

Figure 1 is a side elevation of the lubricator detached from operative position,

Fig. 2 is a side view of the lubricator in operative position,

Fig. 3 is a front view of the lubricator,

Fig. 4 is a vertical sectional view, taken through the reservoir,

Fig. 5 is a vertical elevation of the lubricant conveying pipe detached from operative position and showing the same partially in section,

Fig. 6 is a sectional view on the line 6—6 of Fig. 4.

Fig. 7 is a section through the reservoir, showing the oil level indicator therefor.

Referring to the drawings in detail, the

numeral 1 designates a bracket arm that has one end secured to the main frame A of a locomotive engine by means of suitable fastening elements, designated 2. The arm 1 extends outwardly from the frame, as shown in the drawings, and forms a support for a reservoir 3. The reservoir 3 is provided at two of the opposing sides thereof with straps 4, and the outer end of the arm 1 is provided with a vertical extension or arm 5, which is formed integral with the arm 1 and extends through the straps 4 on one side of the reservoir structure 3. The straps 4 at the opposite side of the reservoir 70 structure receive a vertical arm 6, which has its lower end resting on the horizontal arm 1 and is provided with a lateral extension 7, which is secured to the arm 1 by means of a suitable fastening element 8. The reservoir 75 1 has an inlet opening in the upper or top wall thereof, which is normally closed by means of a hinged door 9. When the door 9 is in operative or closing position, the same is retained in the mentioned position by 80 means of a suitable resilient fastener 10, which is carried by one of the side walls of the reservoir and is adapted to engage over the door 9, and is provided with a manipulating element 11 disposed, normally, 85 above the plane of the door 9. Downwardly converging baffle plates, designated 12, depend from the walls of the inlet opening and have their lower ends provided with opposing flanges that support a suitable screen or 90 straining element 13. The lower wall of the reservoir 3 is provided with a discharge or outlet opening 14, which communicates with an opening in the lower wall of a hollow cylindrical body 15, and is positioned 95 within the reservoir 3. The wall of the hollow body 15 is provided with a plurality of perforations, designated 16, and the upper end of the body 15 is closed by means of a closure 17. The perforated hollow body 15 100 serves as a strainer through which the oil has to pass before being discharged through the discharge port or opening 14 in the lower wall of the body of the reservoir. A controlling stem 18 is mounted for vertical 105 reciprocating movement within the reservoir 3, and has its lower end reduced, as shown at 19, and extended through the closure 17 and through the body 15, and has the lower terminal thereof pointed to extend into the 110 opening or discharge port 14 when the stem is moved downwardly, so as to close the port

14 and prevent the flow of lubricating oil therethrough. The upper end of the reduced portion 19 is threaded for engagement with the opening in the closure 17 through which the reduced end 19 extends. The upper end of the stem 18 projects through the upper wall of the reservoir body 3 and is provided with a head 21, which can be conveniently grasped by the hand of the operator so as to effect rotation of the stem so as to admit of the latter being moved either in an upward or downward direction. A coiled spring 22 encircles the upper end of the reduced portion 19 of the stem 18 and is interposed between the closure 17 and the shoulder formed on the stem 18 by reducing the stem. When the stem 18 is moved downwardly, the spring 22 will be compressed and exert an upward force on the stem 18 and cause tight engagement between the threaded portion 20 on the reduced end 19 of the stem 18 and the threaded wall of the opening in the cover 17, so as to prevent rotation of the stem 18 when the reservoir is subjected to jar or vibration. When the stem 18 is adjusted upwardly, the spring 22 will still partially be tensioned, and exert a similar upward force on the stem 18 so as to cause frictional engagement between the threaded portion 20 and the threaded wall in the cover 17, so as to prevent rotation of the stem 18 when the reservoir 3 is vibrated during the travel of the engine. Mounted within the reservoir body 3 is a float 23, to which is secured a vertically disposed rod 24, which extends through a sleeve 25 mounted in the upper wall of the reservoir body 3. The upper or outer end of the rod 24 is provided with a head 26, which is adapted to serve as an indicator. When the reservoir is filled with oil the float 23 will be raised upwardly and effect raising of the rod 24. The rod 24 and head 26 will serve as means by which the amount of oil within the reservoir can be determined, as the point to which the head, or indicator, will be raised will be determined by the position of the float 23 within the reservoir.

A feed pipe 27 has one end communicating with the discharge port 14, in the lower wall of the hollow cylindrical body 15, and the said pipe projects into the upper end of a relatively large pipe 28, the upper end of the latter pipe being connected, by a suitable joint, to the lower wall of a reservoir 3. The pipe 28 is provided with a sight opening 29 therein, which is disposed opposite the terminal of the inner end of the feed pipe 27, so as to admit of the amount of oil being discharged through the pipe 27 being determined. The pipe 28 has a lateral bend, as shown at 30, and has the lower or free end thereof received by the upper end of a lubricant conveying pipe 31. The upper end of the pipe 31 has connection with

one of the leaves of a leaf hinge 32, the other leaf of the hinge is pivotally connected to one arm of an L-shaped bracket 33, by means of a bolt 34. The other arm of the bracket 33 has connection with the upper end of an upright 35 by means of a fastening element 36. The upper end of the upright 35 is terminally extended laterally, as shown at 37, and engages beneath the element 1 and is secured thereto by means of securing elements 38, and the lower end of the upright 35 is deflected inwardly, as shown at 39, and provided with a rectangular shaped opening 40. The lubricant conveying pipe 31 has a filler 42 therein formed of suitable absorbent material. The lower end of the pipe 31 is curved in conformity to the curvature of the inner face of the flange B of a wheel A, and in the upper inner side of this curved end the pipe is provided with a reduced outlet 43 which is adapted to be positioned directly opposite the inner face of the flange B when the device is in applied position. A guide 44 is secured to the inner side of the pipe 31 at 45, and it is located directly opposite the outlet opening 43. The guide 44 and the opposing portion of the lower end of the pipe 31 form a recess 46 which is adapted to receive the flange B, and the opposing walls of this recess are adapted, by reason of their engagement with the inner and outer faces of the flange B, to hold the lower end of the pipe 31 in engagement with the flange B regardless of any turning or transverse movements that the wheel may have with relation to the frame A. The flange B of the wheel C travels, during the rotation of the wheel C, through the recess 46, and the lower end of the filler 42, contacts with the inner face of the flange B and applies a coating of oil to the inner side of the flange during the rotation of the wheel.

A split collar 47 encircles the lower end of the pipe 31, and has its opposite ends 48 extended in parallelism and has fitted therebetween one end of a rod 49, the opposite end of the rod 49 being slidably received by the opening 40 formed in the inwardly deflected portion 39 of the vertical upright 35. The width of the opening 40 is considerably larger than the diameter of the rod 49, and the said rod 49 is adapted to have longitudinal adjustment through the opening 40, and to be held in different adjusted positions by means of a nut 50, which is turned on the outer end of the rod 49 and adjustable against the outer face of the inwardly deflected portion 39. A coiled spring 51 encircles the rod 49 and is interposed between the inwardly deflected portion 39 of the upright 35, and the ears 48 on the collar 47. The spring 51 serves as a cushion and will admit of the pipe 31 being moved in the direction of the upright 35, but will return 130

the pipe to normal position after the force, which effected movement of the pipe 31 in the direction of the upright 35, has been removed. The hinge 32 admits of the pipe 31 having vertical movement should the wheel C be moved vertically during rotation thereof, and by virtue of the fact that the element 34 pivotally secures the upper hinge 32 to the adjacent arm of the bracket 33, the 10 pipe 31 can have relative lateral movement should the wheel C have lateral movement during rotation thereof.

It is evident that various changes might be resorted to in the construction, form and 15 arrangement of the several parts without departing from the spirit and scope of the invention as claimed.

Having thus described my invention what I claim as new is:

20 1. A wheel flange lubricator including a vertical bracket arm provided with angular members, a hinge having one of its leaves pivoted to one of said members, a lubricant conveying pipe having its upper end secured 25 to the other leaf of the hinge, a rod con-

nected to the lower end of the pipe and having slideable engagement with the other of said members, and a spring surrounding the rod and located between said other member and the pipe.

30

2. A wheel flange lubricator including a horizontal bracket arm provided with a pair of vertical members, a reservoir mounted upon the horizontal arm between said members, and means engaging said members and 35 reservoir.

3. A wheel flange lubricator including a reservoir having an outlet opening, a strainer surrounding said opening and provided with a top wall, a valve stem having 40 threaded engagement with said wall and provided with a shoulder, and a spring located between said wall and said shoulder.

In testimony whereof I affix my signature in presence of two witnesses.

ALEXANDER C. McCLURE.
